SKID FENDER FOR USE IN THE LAUNCHING
OF SHIPS' LIFEBOATS

John Blain Hunt, Penylan, Cardiff, Wales

Application July 28, 1942, Serial No. 452,580
In Great Britain March 13, 1942

2 Claims. (Cl. 9—22)

This invention comprises improvements in and relating to skid fenders for use in the launching of ships life boats irrespective of list and trim of the vessel, particularly in the condition of emergency often obtaining at the present time at sea, when life boats have to be outboard stowed owing to the abnormal time occupied in the operation of getting the life boats outboard from the normal inboard stowed position and refers to skid fenders which are secured to the outboard side 10 of the life boat.

The object of the present invention is to provide skid fenders which are flexible in that they can be readily accommodated to the contour shape of the cross-section of the life boat without the necessity of templating and fitting of the fenders on board the vessel or of notching to fit over the bilge or hand rail, whilst at the same time providing nosing irons or runners which are definitely continuous so as to present an unbroken surface to the vessel side in the event of contact therewith during launching.

Referring to the drawing:

Figure 1 is an end view of a ships life boat with the gunwale in section, fitted with a skid fender according to this invention.

Figure 2 is a front elevation of a skid fender according to this invention in position on a ships life boat.

Figure 3 is a section at 3—3 in Figure 1.

Figure 4 is a perspective view of the nosing iron or runner together with the gunwale attachment, whilst,

Figure 5 is an elevation of a locating member for the lower end of the nosing iron or runner, which may be used with this invention.

In carrying the present invention into practice as shown upon the accompanying drawing, the skid fender consists essentially of the tubular or other suitably shaped member 7 which forms a nosing iron or runner which is shaped to part of the contour in cross-section of the boat 8. The member 7 is provided with brackets 9, 10. To these brackets 9, 10 are secured blocks 11, 12 which are adapted to act as distance pieces between the boat 8 and the member 7.

The upper end of the member 7 is provided with a gripe gunwale fitting 14 which embraces the gunwale 15 of the boat 8.

The lower end of the member 7 is formed with an eye 16 in which is secured the lashing wire or rope 17.

The lashing wire or rope 17 is passed under the keel 18 of the boat 8 to another gunwale fitting 19, which comprises the screwed eye-bolt

20 which is mounted in the fitting 19. This arrangement allowing for the quick release of the skid fender after the launch of the boat.

If desired a locating member as shown in Figure 5 may be employed for locating the lower end of the nosing iron or runner 7, in which case the nosing iron or runner 7 would be of a greater length, the end 21 of which is flattened and positioned around part of the flattened portion is a locating member, which in this case is in the form of a clamp 22.

This clamp 22 consists of two parts which are divided and are adapted to surround part of the flattened portion 21 of the nosing iron or runner 7. Lugs 23 are provided on each side of the clamp 22 through which bolts 24 are passed to secure said clamp 22 in position on the runner 7.

The one half of the clamp 22 is provided with an upstanding part 25 which forms an abutment or stop which is adapted to be positioned against the side of the keel 26 of the life boat 27.

Mounted on the end of the flattened portion 22, which preferably extends beyond the keel 26 of the boat 27 is a shackle member 28 to which is secured the lashing wire or rope 29 which in turn is secured to the eye-bolt of the adjustable gunwale fitting as shown in Figure 1 for securing the skid fender 7 in position on the life boat.

It will be seen that skid fenders according to this invention eliminates the necessity for the templating and fitting on board the vessel carrying the boats, by craftsmen, as a standard skid fender is provided which is applicable to all sizes of life boats, other than in special cases where vessels fitted with heavy bellings or overhanging decks would require vertically extended gunwale fittings to prevent accident to the personnel of the life boat when launching on the high side of a listed vessel.

I claim:

1. A skid fender for use in the launching of ships life boats, comprising in combination, a runner shaped to part of the contour of the cross-section of the boat, a gunwale fitting mounted on said runner which is adapted to embrace the gunwale of the boat, brackets on said runner which are adapted to carry distance pieces to hold the runner from the body of the boat, a lashing secured to said runner, a member secured to said lashing for securing the skid in position and a gunwale fitting which is adapted to be mounted on the boat which permits of the quick release of the member secured to the lashing to permit of the release of the skid fender.

2. A skid fender for use in the launching of ships life boats, comprising in combination, a runner shaped to part of the contour of the cross-section of the boat, a gunwale fitting mounted on said runner which is adapted to embrace the gunwale of the boat, brackets on said runner which are adapted to carry distance pieces to hold the runner from the body of the boat, an extension of said runner, an adjustable locking member which is mounted on said runner ex-

10 tension, part of which is adapted to engage the keel of the life boat, a lashing for securing the skid fender in position secured to the runner, a member secured to said lashing for engagement with a gunwale fitting, and a gunwale fitting which is adapted to be mounted on the boat which permits of the quick release of the member secured to the lashing to permit of the release of the skid fender.

JOHN BLAIN HUNT.
